DESIGN FOR AN EVENING WRAP

Abraham H. Morris, New York, N. Y.

Application January 14, 1939, Serial No. 82,353

Term of patent 3½ years

To all whom it may concern:

Be it known that Abraham H. Morris, a citizen of the United States and resident of New York city, in the county of New York, State of New York, has invented a new, original, and ornamental Design for an Evening Wrap, of which the following is a specification, reference being had to the accompanying drawing, forming part thereof, and in which,

Fig. 1 is a front view of an evening wrap embodying my design showing the detachable skirt portion in partially open position.

Fig. 2 is a rear view of the same.

I claim:

The ornamental design for an evening wrap substantially as shown and described.

ABRAHAM H. MORRIS.
